AUTOMATIC DRAW-OFF ROLLER MECHANISM FOR FULL FASHIONED KNITTING MACHINES

Karl R. Lieberknecht, Oberlungwitz, Germany,
assignor to Kalio Inc., New York, N. Y., a corporation of New York

Application October 6, 1933, Serial No. 692,368

13 Claims. (Cl. 66—149)

This invention relates to a device for automatically controlling the tension upon the draw-off roller of a full fashioned knitting machine so that the tension under which the fabric is drawn off may be decreased as the width of the fabric decreases, and increased as the fabric width increases, so that a greater or less tension may be applied to the fabric at any desired time irrespective of its width or whether it is increasing or decreasing and so that the tension may be entirely relieved when desired without disarranging the tension control for other times.

It has been the practice to maintain the tension upon the draw-off roller by means of a weight suspended from a rope the other end of which is wound around a pulley keyed to the roller shaft, the weight being increased or decreased manually by the operator of the machine as required. This introduces an undesirable human factor since the operator may forget to remove or add weights at the proper times with the result that the loops of the fabric are elongated when they should be uniform and vice versa, thus marring the desired character and quality of the fabric as well as placing an undue strain upon the needles which has frequently resulted in bending or breaking them. Furthermore, if insufficient tension is applied to the fabric the loops may not be cast off. The fabric will then load up on the needles.

By the present invention the tension upon the draw-off roller is maintained by weight as in the past, but the control and varying of the weight and consequently of the tension is performed entirely automatically and without the intervention of the operator. Furthermore, means is provided wherefore the utmost flexibility in varying the tension is secured in that at any desired time any desired increase as well as decrease of tension is made possible, and this is done automatically in accordance with a prearranged schedule.

Various styles of stockings require varying amounts of tension applied at varying times. By this invention the desired amounts and the proper variation thereof are obtained with great ease and accuracy.

As an illustration of the complicated tension requirements frequently encountered, the manufacture of stockings upon single unit knitting machines is an excellent example. During the knitting of the leg it is necessary to decrease the tension several times at certain definite courses. When the heel tabs are knit all tension should be removed for a certain number of courses

after which a certain amount of tension is required during the completion of the heel tabs. Thereafter when the sole portion is begun the tension is again increased and thereafter decreased at intervals until the toe is completed. When a new stocking is begun the tension must, of course, be restored to its original value and the cycle repeated. By this invention all of these changes in tension are automatically performed.

One form of the invention which has been selected solely for purposes of illustration is shown in the following drawings, in which

Figure 1 is a fragmentary diagrammatic view in perspective of a full fashioned knitting machine showing the tensioning device applied thereto;

Fig. 2 is an end elevation of the tensioning device;

Fig. 3 is a fragmentary end elevation of a part of the tensioning device showing the tensioning weights in different positions;

Fig. 4 is an enlarged view of a weight holder;

Fig. 5 is an end elevation of the mechanism for eliminating all of the tension; and

Fig. 6 is an enlarged view of the tension rope pulley and its associated operating mechanism.

As the knitting progresses on needles 2 the completed fabric is drawn off and wound upon a draw-off roller 3. Draw-off roller 3, of which there is one for each section of the machine, is fastened to a shaft 4 on one end of which is loosely mounted pulley 5, the operative connection between it and the shaft 4 being a ratchet 5^b attached to the shaft and a pawl 5^a pivoted upon the pulley. Obviously the pulley may be disengaged from the shaft at any time simply by raising pawl 5^a. Attached to pulley 5 and wound around it a few turns is a rope 6 which, as will be hereinafter explained, is equipped with a number of weights by means of which the desired amount of tension is communicated to the draw-off roller 3 and consequently to the fabric wound thereon. Rope 6 is led from pulley 5 over fixed

guide pulleys 7, 8 and 9 mounted upon a frame 10 and has attached to its free end an adjustable counter-weight 11. Counter-weight 11 is normally supported upon a stop lever 12 which may be swung aside to permit the counter-weight to drop in which case it comes to rest upon a stop 13 adjustably attached to frame 10. Thus counter-weight 11 which, in the ordinary manually operated draw-off device, supplies the weight

which creates the tension, in this invention merely acts as an anchor for the end of the rope in 55

one or the other of the two positions referred to above.

Upon rope 6 between guide pulleys 7 and 8 are suspended a series of weights, four being shown 5 at 14, 15, 16, and 17, but which may be of any desired number. Each weight may be composed of several individual weights, any number of which may be removed thus giving great flexibility to the tension control. Weights 14 to 17 10 may be suspended in any desired way, that shown consisting of a fork 14^b terminating at its lower end in a platform 14^c upon which the removable weights are supported, and having between its arms pulleys 14^c and 14^d over and under 15 which, respectively, rope 6 passes. By this arrangement each of the weights 14 to 17 hangs in a small bight of rope 6. Attached to the top of each fork 14^b is a rope 14^a which passes over guide pulleys 14^e in the top of frame 10, the other 20 end of the rope hanging free but being equipped with an adjustable stop 14^f. As rope 6 unwinds from pulley 5 as the length of the completed fabric increases, that portion of rope 6 hanging between guide pulleys 7 and 8 becomes longer. 25 Consequently weights 14 to 17 which are suspended in this section move downwardly. When the length of this portion of rope 6 has increased enough one of the stops 14^f will engage with frame 10 adjacent pulley 14^e and any further 30 lengthening of rope 6 will eliminate the tension provided by this particular weight since its limit of descent has been reached. The same is true of the other weights which are similarly arranged. The total weight of weights 14 to 17 which, as 35 already stated, may be varied at will, determines the normal tension upon the rope 6 and consequently upon the fabric drawn off. The decreasing of this tension is controlled by the position of each of stops 14^f. By these means any 40 amount of tension may be applied to the fabric and any amount of it removed at any desired time.

When it is desired to again increase the tension, for example, at the beginning of the sole portion of a stocking knit on a single unit machine, 45 the weights, some of which will normally be suspended from the frame 10 through engagement of one or more stops 14^f with it, are again picked up by that part of the rope 6 between pulleys 7 and 8 by shortening the rope. This is accomplished as follows: Counter-weight 11 has been resting on stop lever 12. This stop is now swung out of position so that weight 11 is released and falls carrying rope 6 with it until it encounters stop 13. This will shorten the rope between pulleys 7 and 8 and cause it to again assume the support of weights 14 to 17 or as many of them as desired, depending upon the adjustment of stops 14^f and the position of stop 13. Thereafter the device operates as before, the weights descending as 60 the length of rope 6 increases until they are brought to rest by stops 14^f, as already described.

Stop lever 12 is automatically removed from under counter-weight 11 by the following means: Stop lever 12 forms one arm of a bell crank 65 which is pivoted to any suitable part of the machine, the other arm 25 of which carries a cam roller shaft 25^b upon which a cam roller 25^a is slidably and rotatably mounted. Cam roller 25^a is provided with a collar 25^c which engages a fork 24 in one end of an arm 24^a. The other end of arm 24^a is connected to a rod 23 which may slide longitudinally in suitable brackets such as 30. The other end of rod 23 connects with a bell crank 22 which is adapted to be rocked by 70 means of a pattern chain 21. When a suitable 75

button 20 engages with bell crank 22 rod 23 will be slid to the right against the tension of spring 31 and cam roller 25^a will also be moved to the right into the path of cam 26 on the main cam shaft. When the high portion of cam 26 passes under roller 25^a arm 25 upon which the roller is mounted will be raised. Consequently stop lever 12 which forms the other arm of the bell crank will be swung to the right and from underneath counter-weight 11. Thereupon counter-weight 10 11 will fall, as already described, until it encounters stop 13 when it will again come to rest. Rope 6 will be shortened an amount equal to the distance counter-weight 11 has moved and all or some of weights 14 to 17 will again be supported by rope 6. In this way the tension upon the finished fabric may be automatically decreased at will and then increased and then decreased again at any time and to any degree desired.

At certain times it is necessary or desirable to 20 eliminate all tension from the fabric for several courses as when knitting the first courses of the heel tabs on a single unit knitting machine. This is accomplished by rotating the draw-off roller 3 against the pull of rope 6 thus temporarily 25 eliminating the effect of the tensioning weights without disturbing their adjustment. The mechanism employed may be, in part, that described in United States Letters Patent No. 1,878,868 granted to Karl Willi Lieberknecht, on September 20, 1932, for removing the tension during the pressing off operation for each course. It consists essentially of a disc 50 keyed to shaft 4 or attached to draw-off roller 3 and an arm 51 swingably mounted on shaft 4 and provided with 30 an eccentric cam or inclined surface 52. Between disc 50 and cam 52 a friction roller 53 is loosely mounted. This is normally supported by a stationary stop 54 which maintains it out of 35 operative engagement between cam surface 52 and disc 50. To the free end of lever 51 is pivotally connected one end of a link 55, the other end of which is pivoted to one end of a rock lever 56 which is rockably mounted upon a suitable pivot 58 intermediate its ends. The other end of rock lever 56 carries a cam roller 59 which can engage with a cam 60 on the main cam shaft. When in such engagement with the high part of the cam, arm 51, link 55, and lever 56 will first 40 wedge roller 53 between disc 50 and cam 52 and 45 further motion will rotate shaft 5 slightly in a direction opposed to that caused by rope 6. As long as this condition is maintained all tension is removed from the fabric. Obviously this will occur at each rotation of cam 60 on the main cam 50 shaft or, in other words, during the knitting of each course, as long as cam roller 59 is in engagement with the high part of cam 60. When cam roller 59 leaves the high part of cam 60, arm 51 will rock down again, wedge roller 53 will 55 strike stop 54, which will disengage it from between disc 50 and cam surface 52 allowing the normal tension to be again applied to draw-off roller 3 through rope 6. Since, in addition, the tension should be removed during the knitting of several entire courses when the heel tabs are begun as already explained means, other than cam 60, must be provided to maintain wedge roller 53 in wedging engagement between disc 50 and cam surface 52. To this end a pin 41 is 60 affixed to rock lever 56 adjacent cam roller 59. A lever 36 is rockably mounted upon a suitable bracket 37 attached to the frame of the machine. One end of lever 36 terminates in a hook 36^a adapted to engage with pin 41 when roller 59 is 65 70 75

riding upon the high part of cam 60. The other end of lever 36 is engageable with a cam block 35 mounted upon a longitudinally slidable rod 34. As shown in Fig. 1 when rod 34 is slid to the right cam block 35 will engage with the free end of lever 36 and will elevate it. This will cause the other end 36a of lever 36 to be depressed and to engage with pin 41 on lever 56 and will prevent cam roller 59 from thereafter following the contour of cam 60. When slide rod 34 is slid to the left again cam piece 35 is disengaged from lever 36 permitting end 36a to rise under the urge of spring 39, and to disengage from pin 41.

Automatic control of slide rod 34 may be provided by the same pattern chain 21 which controls the other slide rod 23. To this end slide rod 34 is connected to another bell crank 34a similar to and mounted adjacent to bell crank 22 which operates rod 23. When a suitable series of buttons 32 on pattern chain 21 engages with bell crank 34a rod 34 is slid to the right to move cam piece 35 into action. When buttons 32 disengage from bell crank 34a rod 34 returns to its original position to the left under the urge of a spring 43 and roller 59 again rests upon cam 60. After the completion of a stocking the tensioning device may be reset into its original state by manually raising counter-weight 11 onto stop lever 12 and winding up rope 6 on pulley 5. In fact pulley 5 affords a means of manual readjustment at any time desired.

By the above mechanisms the control of the tension upon the completed fabric is made entirely automatic throughout the knitting of a stocking. The device may be added to a standard knitting machine without great expense and without materially affecting the standard parts or the usual attachments. It insures that the correct tension will be applied at the proper time and eliminates the human factor which has been responsible for much defective fabric.

What I claim is:

1. In a flat knitting machine having a draw-off roller, means for applying a constant rotative tension to the draw-off roller, means for automatically fractionally reducing said tension in timed relation to the knitting, and means for automatically fractionally increasing said tension also in timed relation to the knitting.

2. In a flat knitting machine having a draw-off roller, means for applying a constant rotative tension to said roller, means for automatically fractionally decreasing said tension a predetermined amount, means for automatically fractionally increasing said tension again a predetermined amount, and means for completely neutralizing the rotative effect of said rotative tension on said roller, all of said alterations of tension being effected at predetermined times in relation to knitting.

3. In a flat knitting machine a draw-off roller, a pulley operatively fixed with respect to said roller, a rope wound around said pulley, a series of weights each supported by said rope independently of the others, means for automatically relieving said rope from the weight of each weight in a predetermined order and time sequence, and means for automatically restoring to said rope one or more of said weights.

4. In a flat knitting machine a draw-off roller, a pulley operatively fixed with respect to said roller, a rope wound around said pulley, a series of weights each supported by said rope independently of the others, means for automatically re-

lieving said rope from the weight of each weight in a predetermined order and time sequence, means for automatically restoring to said rope one or more of said weights, and means for neutralizing the effect of said weights upon said pulley, all of said alterations of tension being effected at predetermined times in relation to knitting.

5. In a flat knitting machine a draw-off roller, a pulley operatively fixed with respect to said roller, a rope wound around said pulley, a series of weights each supported by said rope independently of the others, means for automatically relieving said rope from the weight of each weight in a predetermined order and time sequence, means for automatically restoring to said rope one or more of said weights, and means for neutralizing the effect of said weights upon the said pulley throughout the knitting of a predetermined number of consecutive courses.

6. In a flat knitting machine having a draw-off roller, means for applying a constant rotative tension to the draw-off roller, means for automatically fractionally reducing said rotative tension a predetermined amount, means for increasing said rotative tension a predetermined amount, and means for automatically controlling said tension increasing means.

7. In a flat knitting machine having a draw-off roller, means for applying a constant rotative tension to the draw-off roller, means for automatically fractionally reducing said rotative tension a predetermined amount, means for increasing said rotative tension a predetermined amount, and means for automatically controlling said tension increasing means operated by a pattern chain.

8. In a flat knitting machine having a draw-off roller, means for applying a constant rotative tension to said roller, means for automatically fractionally decreasing said tension a predetermined amount, means for automatically increasing said tension again a predetermined amount, and means for completely neutralizing the rotative effect of said rotative tension on said roller, said tension increasing and neutralizing means being governed by a pattern chain.

9. In a flat knitting machine having a draw-off shaft, a roller keyed to said shaft, a pulley keyed to said shaft, a rope one end of which is wound around said pulley, the other end of which is attached to a counter-weight, a loop in said rope, a multiplicity of weights separately supported in said loop, means for successively relieving said rope from the weight of said weights as it is unwound from said pulley, and means for shortening said loop to suspend said weights from said rope again.

10. In a flat knitting machine having a draw-off shaft, a roller keyed to said shaft, a pulley keyed to said shaft, a rope one end of which is wound around said pulley the other end of which is attached to a counter-weight, a loop in said rope, a multiplicity of weights separately supported in said loop, means for successively relieving said rope from the weight of said weights as it is unwound from said pulley, and means for shortening said loop to suspend said weights from said rope again, said lifting means for each weight comprising a rope attached by one end to each weight and passing over a superimposed fixed guide and having an adjustable stop beyond said guide for limiting the distance through which each weight can descend.

11. In a flat knitting machine having a draw-off shaft, a roller keyed to said shaft, a pulley keyed to said shaft, a rope one end of which is

- wound around said pulley the other end of which is attached to a counter-weight, a loop in said rope, a multiplicity of weights separately supported in said loop, means for successively relieving said rope from the weight of said weights as it is unwound from said pulley, and means for shortening said loop to suspend said weights from said rope again, said shortening means comprising a removable support beneath said counter-weight, means for removing it in timed relation to the knitting to permit the counter-weight to drop and an adjustable secondary support beneath said removable support to receive said counter-weight.
- 5 13. In a flat knitting machine having a draw-off shaft, a roller keyed to said shaft, a pulley keyed to said shaft, a rope one end of which is wound around said pulley the other end of which is attached to a counter-weight, a loop in said rope, a multiplicity of weights separately supported in said loop, means for successively relieving said rope from the weight of said weights as it is unwound from said pulley, means for shortening said loop to suspend said weights from said rope again, said shortening means comprising a removable support beneath said counter-weight, and pattern chain means for removing it in timed relation to the knitting to permit the counter-weight to drop and an adjustable secondary support beneath said removable support to receive said counter-weight.
- 10 14. In a flat knitting machine having a draw-off shaft, a roller keyed to said shaft, a pulley keyed to said shaft, a rope one end of which is wound around said pulley the other end of which is attached to a counter-weight, a loop in said rope, a multiplicity of weights separately supported in said loop, means for successively relieving said rope from the weight of said weights as it is unwound from said pulley, means for shortening said loop to suspend said weights from said rope again, and means for operating said shortening means in timed relation to the knitting controlled by a pattern chain.
- 15 15. In a flat knitting machine having a draw-off shaft, a roller keyed to said shaft, a pulley keyed to said shaft, a rope one end of which is wound around said pulley the other end of which is attached to a counter-weight, a loop in said rope, a multiplicity of weights separately supported in said loop, means for successively relieving said rope from the weight of said weights as it is unwound from said pulley, means for shortening said loop to suspend said weights from said rope again, said shortening means comprising a removable support beneath said counter-weight, and pattern chain means for removing it in timed relation to the knitting to permit the counter-weight to drop and an adjustable secondary support beneath said removable support to receive said counter-weight.
- 20

KARL RICH. LIEBERKNECHT.
